C. T. GRILLEY, OF NEW HAVEN, CONNECTICUT, ASSIGNOR TO THE GRILLEY COMPANY.

Letters Patent No. 66,284, dated July 2, 1867.

IMPROVEMENT IN CAPPING PAD-SCREWS.

The Schedule referred to in these Letters Patent and making part of the same.

TO WHOM IT MAY CONCERN:

Be it known that I, C. T. GRILLEY, of New Haven, in the county of New Haven, and State of Connecticut, have invented certain new and useful improvements in Capping Pad-Screws; and I hereby declare the following to be a full, clear, and exact description of the same, reference being had to the accompanying drawings, in which—

Figures 1 and 2 are views of the cap and screw detached from one another; and

Figure 3 represents the screw capped and drilled or perforated in accordance with my invention.

The pad-screw, as is well known, instead of being nicked in the top or face of the head like the ordinary screw, has holes bored or drilled in the side of the head, which answer the same purpose as the nick in the common screw, and yet admit of the surface or top of the head being presented to the eye unbroken and unimpaired in appearance. In capping this screw, *i. e.*, in applying to the screw a metal cap which is fitted to and closed upon the head, and serves to both ornament and protect the same from rust, &c., great difficulty is experienced in finding the holes in the head, which are of course covered and hidden by the cap-blank. All of the various ways devised for finding these holes, either by striking the capped head lightly with a mallet or hammer until that part of the cap over the hole is struck and depressed, which is the most common method, or by the employment of other appliances and machinery which need not be here mentioned, are defective on many accounts. Not only do they take up much time and cause a needless expenditure of labor, but the work is not perfectly done, and the cap is often damaged and rendered worthless. It is in fact practically impossible to make perfect screws so long as the hole in the screw is covered by the cap-blank.

The object of my invention is to overcome this difficulty, which I accomplish in the following manner: Instead of perforating the screw-head before the cap is applied to it, the screw-head, as well as the cap, should be blank, *i. e.*, without hole or perforation. In this state the two are united together, the cap being closed upon the head by any of the methods now employed for a like purpose. After this has been accomplished, I proceed to form the holes in both screw and cap by drilling or boring through from one side to the other of the head. By this simple but effective means no time is wasted in vain attempts to find the hidden hole in the screw-head, and the work is done well and quickly. The cap is not injured or defaced, and the tendency of the cap to throw up or separate from the head, which is noticeable at times when the ordinary method of forcing the hole is employed, is effectually prevented.

In figs. 1 and 2 of the drawings, the cap and screw are represented at A and B respectively, separate from each other, and not perforated. While in this condition the cap is closed upon screw-head, as shown in fig. 3, and after this the hole *a* is formed by boring through from one side to the other of the screw-head. Any suitable tool may be used for this purpose, and either one drill may be employed or two. When one is employed the head is drilled about half way through from one side, and then the screw is turned around and the drill is applied at a point on the other side diametrically opposite that where the hole was begun, so as to perforate the head until it meets with the other hole. In case two drills are used they work simultaneously from opposite sides of the head, so as to meet in the centre. In all cases, whether one or more drills are used, they should work from the sides or exterior of the head toward the interior, so as to avoid forcing out the cap from the head.

By my invention I am enabled to economize time and labor. The time consumed in the operation is shortened, as above explained, and besides but one operation is requisite where two were before, and I moreover do the work more thoroughly and neatly, and produce a better and more perfect capped screw than can be made by the old methods.

Having described my invention, and the manner in which the same is or may be carried into effect, I shall now state my claims, as follows:

In the manufacture of capped pad-screws I claim the method of drilling or perforating the screw-head and cap-blank, after the two have been united together, and at one operation, substantially as herein specified.

In testimony whereof I have signed my name to this specification before two subscribing witnesses.

C. T. GRILLEY,
